EDWARD F. GILBERT, OF LYONS, NEW YORK.

Letters Patent No. 73,796, dated January 28, 1868.

IMPROVED SCREEN-ATTACHMENT FOR WASH-STANDS.

The Schedule referred to in these Letters Patent and making part of the same.

TO ALL WHOM IT MAY CONCERN:

Be it known that I, EDWARD F. GILBERT, of Lyons, in the county of Wayne, and State of New York, have invented a certain new and useful Improvement in Screen-Attachment for Wash-Stands; and I do hereby declare that the following is a full and exact description thereof, reference being had to the accompanying drawings, making part of this specification.

Figure 1 is a perspective view of a wash-stand with my improvement applied thereto.

Figure 2, a top view of the screen, with the wings folded and the screen slid down behind the stand.

Like letters of reference indicate corresponding parts in all the figures.

My improvement consists in an adjustable screen, combined with a wash-stand or commode, for protecting the wall, which screen may be raised, when required for use, or lowered so as to be hidden from view; also, in forming the adjustable screen with expanding wings, so as to afford a large screening-surface, which wings may be folded in a small compass and slid down out of sight, the wings also serving to hold the screen in the elevated position, when expanded, as hereinafter explained.

As represented in the drawings, A is a wash-stand or commode, which may be of any desired form and construction. B is the body or centre of the screen, and C C are the wings, hinged respectively on each side of the body. The screen is preferably covered with simply an oil-cloth, *e*, or any suitable water-proof material.

Back of the wash-stand are secured vertical ways *a a*, provided with grooves *b b*. Within these grooves rest sliding bearings *c c*, extending downwards from screen B. When the screen B is in the elevated position, the wings C C are expanded, and rest over on top of the vertical ways *a a*, and thereby support the weight of the screen and secure it in position.

This screen will protect the wall from being spattered and soiled, which is of very great importance. The device is entirely concealed from view, when not in use, by simply sliding it down, when the stand or commode presents the usual appearance, and its application cannot be detected by a superficial examination. The wings C C serve the purpose of affording a larger screening-surface than would otherwise be the case, and, when expanded, they rest on top the ways *a a*, and retain the screen in the elevated position, and, by being hinged to the body B, they are easily folded into a compact form, and slid down behind the stand.

What I claim as my invention, and desire to secure by Letters Patent, is—

1. The combination of an adjustable screen, covered with oil-cloth or equivalent, with a wash-stand, so arranged that it may be raised or lowered at will, and hidden from view when not in use, substantially as herein set forth.

2. The combination of the wings C C with the adjustable centre, B, so arranged as to expand and retain the screen elevated, or to fold to be depressed from sight, substantially as herein set forth.

In witness whereof, I have hereunto signed my name in the presence of two subscribing witnesses.

EDWARD F. GILBERT.
